UNITED STATES PATENT OFFICE.

FREDERICK M. WHYTE, OF TARRYTOWN, NEW YORK, ASSIGNEE TO HUTCHINS CAR ROOFING COMPANY, OF DETROIT, MICHIGAN, A CORPORATION OF MICHIGAN.

CAR-ROOF.

1,300,076.

Specification of Letters Patent.

Patented Apr. 8, 1919.

Application filed November 1, 1917. Serial No. 199,738.

To all whom it may concern:

Be it known that I, FREDERICK M. WHYTE, a citizen of the United States of America, residing at Tarrytown, in the county of 5 Westchester and State of New York, have invented certain new and useful Improvements in Car-Roofs, of which the following is a specification, reference being had thereto in to the accompanying drawings.

10 The invention relates to car roofs of the flexible type, and it is one of the objects of the invention to obtain a construction in which the roofing sheets may be riveted or otherwise rigidly attached to the carline or 15 roof frame, while at the same time permitting freedom of movement relative to each other. The invention further comprises various specific features as herein-after set forth.

20 In the drawings:

Figure 1 is a transverse section through the car roof;

Fig. 2 is a section on line $\alpha-\alpha$ Fig. 1;

Fig. 3 is an enlarged view of a portion of 25 Fig. 2;

Fig. 4 is a perspective view of the carline.

A are carlines, which as shown are of channel section, with a vertically extending web portion and top and bottom flanges B 30 and C. These flanges are preferably non-parallel, the lower flange extending horizontally across the car and the upper flange conforming to the pitch of the roof. D are purlins which are in sections, extending between carlines and attached thereto by bolting or otherwise securing to the lower flanges C, as indicated at E. The opposite end of each purlin may be attached to the carline by striking a portion F from the web 35 to form a supporting and attachment bracket, secured to the purlin by the bolt F'. G are roofing sheets, which extend between carlines, being rigidly secured by a series of rivets H or other securing means in line.

40 The rigid attachment between the sheet and the carline is not detrimental, providing the sheet is otherwise free, so as to be capable of movement with the carline in any distortion or weaving of the roof frame.

45 It is, however, absolutely necessary to form a weather-proof connection between adjacent sheets, and further to afford support for said sheets intermediate the carlines. To accomplish this, the sheets are permitted to 50 rest directly upon the purlin sections, and

the latter are so fashioned that the free edge of the sheet is lower than the upper flange of the carline. This free edge is then provided with an upturned flange I adjacent to the carline, but preferably providing some clearance, while the opposite or riveted edge of the sheet is extended beyond the carline, and is turned down adjacent to the upstanding flange of the next sheet. As shown, the downturned portion J is further provided with a laterally-extending portion K, which overlies the adjacent sheet to form a better weather seal. A still better weather seal may be formed by providing the sheet with an upwardly-extending bead L adjacent to the edge of the flange K, which stops the water from running into the crevice between the laterally-extending portion K and the adjacent sheet. This bead L may be formed, as shown, of a separate piece riveted to the sheet, or it may be formed in other ways.

With the construction as described, in operation, the weaving of the car frame will produce relative movement of adjacent sheets, which is permitted by the sliding of the free edge of one sheet beneath the weather-proofing flange on the fixed edge of the adjacent sheet. The sheets are also free to slide upon their supporting purlins, which latter are preferably formed of wood, or provided with non-metallic bearing surfaces on which the sheets rest, so as to avoid any abrading action.

The running-board M may be readily attached to this type of roof by supporting brackets N, which may be rigidly secured by bolting or riveting to the carline and the sheet riveted thereto.

What I claim as my invention is:

1. In a car roof, the combination with a plurality of carlines, of roofing sheets having one edge thereof rigidly secured to the respective carlines and the opposite edge extending into proximity to another carline, and means for weather-proofing the joint between the free edge and said carline.

2. In a car roof, the combination with a plurality of carlines, of a roofing sheet rigidly secured to one carline and spanning the space between carlines, with a free edge adjacent to the next carline, and means for weather-proofing the free edge of said sheet, permitting freedom of movement.

3. In a car roof, the combination with a

plurality of carlines, of a roofing sheet extending between carlines, having one edge portion thereof rigidly attached to one carline and the opposite edge portion flanged adjacent to another carline, and weather-proofing means for the flanged edge of said sheet.

4. In a car roof, the combination with a plurality of carlines, of a roofing sheet extending between carlines, having one edge portion rigidly attached to the top of one carline and the opposite edge portion arranged in a lower plane and provided with an upstanding flange adjacent to another carline, and a downturned flange on the rigidly attached portion of the sheet for weather-proofing the upstanding flange of an adjacent sheet.

5. In a car roof, the combination with a plurality of carlines, of a roofing sheet extending between carlines, having one edge portion thereof rigidly attached to the top of one carline, the opposite edge extending into a lower plane and provided with an upstanding flange adjacent to another carline, the rigidly attached edge portion being further provided with a downturned flange embracing the upturned flange of an adjacent sheet, and having a laterally-extending foot flange overlying said adjacent sheet.

6. In a car roof, the combination with a plurality of carlines, of a roofing sheet extending between adjacent carlines, one edge

portion of said sheet being rigidly attached to the top of one carline and the opposite edge portion being arranged in a lower plane and being provided with an upstanding flange adjacent to another carline, the rigidly-attached end portion of said sheet being further provided with a downturned portion embracing the upstanding flange of an adjacent sheet and having a laterally-extending flange overlying said adjacent sheet, and the free edge portion of said sheet having a bead or ridge adjacent to said overlying laterally-extending flange.

7. In a car roof, the combination with a plurality of carlines, of a roofing sheet extending between carlines, having one edge portion thereof rigidly attached to the top of one carline and its opposite edge portion extending into a lower plane adjacent to another carline and provided with an upstanding flange, a downturned flange on the rigidly-secured edge portion for embracing the upstanding flange of an adjacent sheet and weather-proofing the same, and a purlin section extending between carlines, fashioned to support the sheet with its opposite edge portions in different planes.

In testimony whereof I affix my signature in presence of two witnesses.

FREDERICK M. WHYTE
